ROTARY SHEET TRANSFER MECHANISM

Edward F. Dudley, Oak Park, Ill., assignor to
Miehle Printing Press & Manufacturing Company, Chicago, Ill., a corporation of Illinois

Application December 23, 1936, Serial No. 117,391

15 Claims. (Cl. 101—409)

The invention relates to the art of printing and has particular reference to improvements in rotary sheet transfer means to assure perfect register of successive impressions in a multi-unit press such as a multi-color press.

The improvements of the present invention have been especially designed for sheet fed multi-color machines having a plurality of printing couples arranged in tandem for unit operation and wherein the sheets are transferred by one or a plurality of transfer cylinders from one printing couple to the next adjacent printing couple. In multi-color presses of the above type accurate registry is absolutely indispensable if performance of the highest grade is to be secured. Machines as heretofore constructed have only approximated such performance, notwithstanding the mechanical precision of the gear drive for the transfer cylinders since inaccuracy of only a few thousandths of an inch in alignment of the grippers of adjacent transfer cylinders at the moment of transfer is all that is required to destroy an otherwise faultless registration of the sheet. The problem becomes increasingly difficult as the printing couples and transfer cylinders operating as a unit increase in number since any inaccuracy in transfer is generally cumulative as regards the registration of the sheet.

In a two-color planographic offset press, for example, it is desirable to space the printing couples as far apart as possible in order to give adequate drying time for the ink between impressions and to also provide sufficient space between the printing couples to render the same accessible to the pressmen. However important these considerations may be, they can not be attained by sacrificing accuracy in the registration of the impressions from the succeeding printing couples. This has been a real difficulty. The transfer cylinders of a press of this type are geared to each other and to the several printing couples so that all the parts operate in unison. It is well known that pressure applied to the gearing at one point, as a result of an operation on a sheet, is transferred to other parts thereof such as the transfer cylinders and the pressure in many cases has been sufficient to seriously affect the transfer so as to destroy perfect registration of the sheet. Accordingly, an object of the invention is to provide improved rotary sheet transfer means which will assure perfect registry of the successive impression in a multi-color press.

Another object of the invention is to provide 55 rotary sheet transfer members having opera-

tion to transfer a sheet from one member to the other and which will effect said transfer in a manner to maintain accurate register of the sheet.

Another object of the invention resides in the provision of a sheet transfer member having novel means permitting relative movement between the gripper elements of said member and its driving shaft, whereby said gripper elements may be accurately aligned with other gripper elements at the moment of transfer of a sheet to thereby maintain accurate register of the sheet. 5

A feature of the invention resides in the provision of non-rigid connecting means between each transfer member and its driving shaft where- 15 by each member may have adjustment independently of its driving shaft, such as will produce a circumferential displacement of the gripper elements from their normal position. Advantage is taken of this non-rigid drive by directly connecting adjacent transfer members during transfer of a sheet, producing displacement of one or both members from their normal position, if necessary, in order to accurately align the gripper elements thereof at the moment of transfer. 20 Thus register of said sheet is maintained and as each transfer may take place through similar mechanism the number of transfers between 25 printing units is immaterial.

Another object of the invention resides in the provision of transfer means including members each having a non-rigid connection with its driving means and which members will co-act during transfer of the sheet to effect perfect alignment of the gripper elements thereof at the 35 moment of transfer.

With these and various other objects in view, the invention may consist of certain novel features of construction and operation, as will be more fully described and particularly pointed 40 out in the specification, drawings and claims appended hereto.

In the drawings which illustrate an embodiment of the invention and wherein like reference characters are used to designate like parts— 45

Figure 1 shows in diagrammatic side elevation the general arrangement of a two color planographic offset press such as may embody the improved sheet transfer means of the invention;

Figure 2 is a plan view of several co-acting transfer members embodying the features of the invention;

Figure 3 is an elevational view taken substantially along line 3—3 of Figure 2 and showing 55

the co-acting gear segments of adjacent transfer members in meshing engagement;

Figure 4 is a sectional view taken substantially along line 4-4 of Figure 2, showing the manner of journaling the transfer members on their respective drive shaft; and

Figure 5 is an elevational view showing the invention as applied to a flat bed cylinder press.

Referring to Figures 1 to 4 inclusive, the invention is disclosed as applied to a two-color planographic offset press consisting essentially of a main frame 10, preferably made up of two side members and suitable cross members which support the printing couple including a plate or form cylinder 11, a blanket cylinder 12, and an impression cylinder 13, all of which cylinders are intergeared so that they will rotate at the same peripheral speed, said gears being identified by numerals 14, 15 and 16, respectively.

20 The printing plate which is attached to the form cylinder by any suitable mechanism is inked by means of inking mechanism indicated generally by numeral 17, which may include the usual ink fountain and distributing roller, the roller unit, ductor roller for conveying ink from said fountain to said roller unit, and a form roller unit whereby the ink is applied to the printing plate. The cylinder 12 is provided with a resilient surface such as a rubber blanket or the like which receives impressions from the ink plate on the cylinder 11 and transfers said ink impressions to the sheets as they pass between the blanket cylinder 12 and the impression cylinder 13. The sheets to be printed are fed to the impression cylinder 13. In the structure illustrated the sheets are supported by the registering table 18 and transferred from said table to the impression cylinder 13 by stop gripper mechanism carried by shaft 20 to which is fixed gear 21, the same meshing with gear 16 on the impression cylinder, whereby said stop gripper mechanism has rotation in timed relation to that of said cylinder.

After a sheet has received its impression from the first printing unit it is transferred to the impression cylinder 22 of the succeeding printing unit by means of transfer cylinders 23 driven by gears 30 and which cylinders may embody the improvements of the invention. Upon having received its second impression, which results by reason of the sheet passing between the said impression cylinder 22 and the blanket cylinder 24, the same is then delivered to an endless chain 26 which carries a number of delivery grippers such as 27. It will be observed by reference to Figure 1 that the plate, blanket and impression cylinders of each printing unit are geared together and to the transfer members so that all the cylinders are intergeared for synchronous rotation. The transfer cylinders 23 are uniform in diameter and accordingly the gripper elements on each cylinder will travel at the same peripheral speed. The source of power for rotating said cylinders above described may comprise an electric motor 25 connecting by belt 26 with pulley 27. Said pulley drives the pinion 28 meshing with the gear 30 on the forward transfer cylinder.

While in the preferred form only three transfer cylinders or members have been shown, it will be readily understood that any desired number of such cylinders or members may be arranged for the purpose of transferring sheets from one printing unit to another, it being of course understood that each transfer cylinder is provided with gripper elements adapted to en-

gage the sheet and transfer the same when the grippers of the adjacent transfer cylinder are aligned therewith.

In presses of this type it is necessary that the sheet be transferred in a manner to maintain accurate registry for the succeeding ink impressions. An inaccuracy of only a few thousandths of an inch in alignment of the grippers on adjacent transfer cylinders at the moment of transfer is sufficient to destroy an otherwise faultless registration. Such an inaccuracy was unavoidable in machines as heretofore constructed because the transfer cylinders were directly connected to the gear driving said cylinder and which gear was included in the chain of gearing connecting the printing units. Thus pressure applied to the gearing at one point, as a result of an operation on the sheet, was transferred to the impression cylinders, for example, to thereby destroy the accurate alignment of the gripper elements at the moment of transfer.

A feature of the invention resides in a non-rigid drive for each transfer cylinder which permits coaction of the cylinders during transfer to effect perfect alignment of the gripper elements, whereby transfer of the sheet takes place in a manner maintaining accurate register.

Referring more particularly to Figures 2, 3 and 4, a plurality of transfer members are disclosed which may be considered as exemplary of the transfer means in the offset press shown in Figure 1. The shafts 32, journalled by frame 33, have fixed thereto the driving gears 34 which mesh with each other so that said shafts are driven in unison. Each shaft journals a sleeve 35 to which spiders 36 are suitably fixed at intervals along its length and which spiders have secured thereto, as at 37, the semi-cylindrical member 38. Said member forms the drum of the transfer cylinder. Suitably journalled by the spiders of each transfer cylinder is a gripper shaft 40 having fixed thereto a plurality of spaced gripper elements 41 yieldingly forced by springs 42 into contact with pad members 43, the said gripper elements thereby retaining a sheet on the member by holding the same in contact with said pad members. Rocking of said gripper shaft 40 will effect movement of the gripper elements to release a sheet for transfer.

It will be observed that each sleeve 35 journals a transfer member on its respective driving shaft and thus the transfer member is independent of the shaft and may have rotation with respect to the same. Fixed to each sleeve 35 at the ends is an end member or spider 45 which has secured to the drum 38 at points 46. Tie rod 47 extends lengthwise of each transfer member and is joined at its respective ends to the end members 45. The drive to each transfer member takes place through an arm 48 suitably fixed to its respective shaft 32 and located exteriorly of and immediately adjacent the end member 45. The outer end of said arm is provided with diametrically opposed portions 49, which portions house springs 50 adapted to engage therebetween the projecting end of a rod 51 extending from end to end of each transfer cylinder and having secured at each end to a member 45. Said rod also connects with the spiders 36 of its respective transfer cylinder as does also the tie rod 47, as will be clear by reference to Figure 4. The arm 48 having connection with the projecting end of rod 51, through the resilient springs 50, forms a non-rigid connection between the driving shaft 32 and its re-

spective transfer member, the driving impulse being transmitted by arm 48 to a spring 50 through rod 51 to the structure supporting the drum of the transfer member.

5 The driving shafts of said transfer members are interconnected by gears 34 and therefore said shafts will rotate in unison. The driving impulse to each transfer member is transmitted by the non-rigid connection described. Accordingly, 10 the transfer members will also be rotated in unison and as the said members are equal in diameter the gripper elements of each will have the same peripheral speed. However, it is possible by reason of said non-rigid connection to produce a circumferential displacement of the gripper elements of a transfer member within limits permitted by said non-rigid connection, and which displacement will take place independently of the 15 gearing connecting the driving shafts 32. Accordingly, it is possible to effect perfect alignment of the gripper elements on adjacent members at the moment of transfer so that said sheet will be transferred in a manner to maintain accurate register of said sheet.

20 In accordance with the invention this is accomplished by means of gear segments 53, each transfer cylinder carrying a segment and which is secured to the end of a pin 54, projecting from the hub portion 55 integral with the end member 45, the said segment being releasably secured to 25 the pin by nut 56. An opening of suitable size is provided in each gear segment, permitting the gripper shaft 40 of the transfer cylinder to pass through and which also permits possible movement of said gear segment. There is secured to the end of the gripper shaft 40 an arm 51 carrying a roller 58 adapted to ride in a cam race formed in the cam member 60 and in this manner the gripper shafts are actuated to open and 30 close at the proper moment for transferring the sheet. The gear segments are positioned on the transfer cylinders so that the pitch line thereof substantially coincides with the periphery of its respective transfer cylinder and it will further be observed that the gear segments are disposed in 35 horizontal alignment with the gripper elements. During rotation of the transfer cylinders the gear segments on adjacent cylinders have meshing engagement which thereby directly connects the 40 said adjacent transfer cylinders. It is absolutely essential that the gear segments be fixed to the transfer cylinders at a point with respect to the gripper elements thereof so that when the gear 45 segments mesh, proper relative adjustment of the transfer cylinders will result to perfectly align the gripper elements thereof. Even a few thousandths of an inch inaccuracy in alignment of the gripper elements on adjacent transfer 50 cylinders at the moment of transfer is sufficient to destroy the register of the sheet but as a result of the structure of the invention even a relative minor inaccuracy of a few thousandths of an inch can be corrected and the gripper elements perfectly aligned at the moment of transfer. To insure meshing engagement of the gear 55 segments with a pitch line contact alternate segments are pivotally secured to the end members 45 of their transfer cylinder. For example, as shown in Figure 3, the two outer cylinders are 60 pivotally secured in a manner permitting limited oscillating movement with respect to the pin 54. The lower ends of these outer gear segments are yieldingly forced in an outward direction by a coil spring 61 carried by pin 62 secured to the gear 65 segment at one end and having connection at its

other end with the end member 45 by means of the boss 63 integral with and projecting from said end member. The tension exerted by said spring may be adjusted by nut 64. When the gear segments are pivotally secured, as in the two outside transfer members, they have a loose connection with the end member at 65. However, with respect to the center transfer member the gear segment thereof is fixedly secured to pin 54 and is also fixedly secured to the end member at 65. 10

15 By pivotally securing certain gear segments to their respective transfer cylinder and yieldingly forcing the free end thereof outwardly a pitch line contact is assured when adjacent segments mesh during transfer of a sheet. Each transfer cylinder may be described as having a floating relation with respect to its driving means although the driving means will rotate said transfer cylinders in unison. When the gripper elements on adjacent cylinders come together in 20 order to transfer a sheet from one to the other, the gear segments on the respective cylinders will mesh to produce, if necessary, a circumferential displacement of the transfer cylinders in order to accurately align the elements at the 25 moment of transfer. A circumferential displacement is permitted by reason of the floating relation of the cylinders with respect to the driving means. Actually the displacement of the transfer cylinders in order to accurately align the elements at the 30 moment of transfer may not be more than a few thousandths of an inch but as a result of the same any inaccuracy in alignment of the gripper elements at the moment of transfer is corrected. 35

Figure 5 shows the invention as applied to a multicolor flat bed cylinder press. The said press may comprise suitable structure 68 supporting two reciprocating beds 70 and 72. An impression cylinder 73 supported by the driving 40 shaft 74 is adapted to coat with bed 70, while a second impression cylinder 75, supported by shaft 76, is adapted to coat with bed 72. Each cylinder is fixedly secured to its respective shaft and each shaft has suitably fixed thereto, on the gear 45 side of the press, gears 77 and 78, respectively. The press shown in Figure 5 is a two revolution, two color type of flat bed cylinder press, an ink impression of one color being applied by cylinder 73 and the bed 70, and a second ink impression 50 of a different color being applied by cylinder 75 and bed 72. For transferring the sheet from one cylinder to the other a transfer cylinder 80 is interposed therebetween. The driving shaft 81 journals said transfer cylinder so that said cylinder may have rotation relative to its shaft, and arm 48 provides a non-rigid connection between the cylinder and shaft as previously described in connection with the transfer mechanism of Figures 1 to 4 inclusive. Gear 82 is fixed to shaft 81 and is adapted to mesh with gears 77 and 78 so that said impression cylinders have simultaneous rotation with the rotation of the transfer cylinder synchronized to accomplish the transfer 55 of the sheet from one impression cylinder to the other. 60

The transfer cylinder 80, having floating relation with respect to its driving shaft 81, carries a gear segment 53 which is pivoted to the cylinder at 54 and is yieldingly forced outwardly at 70 the lower end thereof by the resilient spring 61 in a manner as described with respect to Figures 2, 3 and 4. The impression cylinders 73 and 75 also carry gear segments 53, which, however, are rigidly secured to their respective cylinders at 54 75

and 65. In operation of the flat bed press described the sheet is fed from the registering table 84 to the cylinder grippers on the impression cylinder 73 which rotates for a half revolution 5 before said sheet is brought into impression with the reciprocating bed 70 and during the next half revolution or more printing of said sheet takes place. Rotation of the cylinder continues for approximately one-fourth revolution to align the 10 grippers of the cylinders 73 and 80 to transfer the sheet to the cylinder 80 which has rotated so that at the moment of transfer the cylinder grippers thereof are properly positioned. When this 15 takes place the gear segments of the two cylinders have meshing engagement to accurately align the gripper elements thereof. The impression cylinder 73 will rotate for three-fourths of a revolution approximately before another sheet is fed thereto. The transfer cylinder will 20 rotate one and one-half revolutions before locating its cylinder grippers in alignment with the cylinder grippers on the impression cylinder 75. Accordingly, the gear segments of these cylinders will mesh during transfer of the sheet, 25 thereby accurately aligning the gripper elements at the moment of transfer. Rotation of impression cylinder 75 which is in a counter-clockwise direction will eventually bring said sheet into contact with bed 72 to apply an impression to 30 said sheet, whereupon the sheet is eventually taken from said impression cylinder by structure which is not disclosed as the same may be of conventional type old and well known in the printing art.

35 The invention is not to be limited to or by details of construction of the particular embodiment thereof illustrated by the drawings, as various other forms of the device will of course be apparent to those skilled in the art without deviating from the spirit of the invention or the scope of the claims.

What is claimed is:

1. In sheet transfer mechanism, members having operation to transfer a sheet from one member to the other, non-rigid driving means for each member, and means on each member having coaction during transfer of the sheet and operative to properly position the members relative to each other, whereby transfer of the sheet 50 will be effected in a manner to maintain accurate register of the sheet, the said proper positioning of the members taking place independently of the driving means therefor.

2. In sheet transfer mechanism, members having operation to transfer a sheet from one member to the other, non-rigid driving means for each member, gripper elements carried by each member for engaging the leading edge of a sheet, and means on each member having coaction 55 during transfer of the sheet and operative to effect alignment of the gripper elements at the moment of transfer, whereby accurate register of the sheet is maintained, the said aligning of the gripper elements taking place independently 60 of the driving means therefor.

3. In sheet transfer mechanism, rotary members each having gripper elements for engaging the leading edge of a sheet, driving means for synchronously rotating the members, each driving 70 means having a non-rigid connection with its member whereby the gripper element thereof may be circumferentially displaced from its normal position with respect to its driving means, and means on each member having engagement 75 during transfer of the sheet to directly connect

the members, whereby said members are positioned relative to each other to accurately align the gripper elements at the moment of transfer.

4. In sheet transfer mechanism, rotary members each having gripper elements for engaging the leading edge of a sheet, interengaging driving means for synchronously rotating the members, each driving means having a non-rigid connection with its member permitting a circumferential displacement of the gripper element 10 thereof from the normal position with respect to its driving means and means on each member adapted to coact during transfer of the sheet, said means having operation to directly connect said members during coaction thereof, whereby 15 said members are positioned relative to each other to accurately align the gripper elements at the moment of transfer.

5. In sheet transfer mechanism, rotary members each having gripper elements for engaging the leading edge of a sheet, driving means for 20 rotating said members in unison, means interposed between each member and the driving means therefor whereby each member has a floating relation with its driving means permitting a circumferential displacement of each gripper element with respect to its driving means, and gear segments on each member having engagement during transfer of the sheet to directly 25 connect the members to accurately align the gripper elements at the moment of transfer.

6. In sheet transfer mechanism, rotary members each having gripper elements for engaging the leading edge of a sheet, driving means for 30 rotating said members in unison, means interposed between each member and the driving means therefor whereby each member has a floating relation with its driving means permitting a circumferential displacement of each gripper element with respect to its driving means, and gear segments on each member constructed and 35 arranged to mesh during transfer of the sheet with a pitch line contact, said gear segments directly connecting the members to accurately align the gripper elements at the moment of transfer.

7. In sheet transfer mechanism, rotary cylinders each having gripper elements thereon, driving shafts, means journaling each cylinder on its driving shaft, a non-rigid connection between each shaft and its respective cylinder, and means carried by each cylinder adapted to coact during 40 transfer of a sheet to directly connect the cylinders.

8. In sheet transfer mechanism, rotary cylinders each having gripper elements thereon, driving shafts, means journaling each cylinder on its driving shaft, resilient means interposed in the connection between each shaft and its respective cylinder, whereby each cylinder has a floating relation with its shaft, and means carried by each cylinder adapted to coact during 45 transfer of a sheet to directly connect the cylinders.

9. In sheet transfer mechanism, rotary cylinders each having gripper elements thereon, driving shafts, means journaling each cylinder on its driving shaft, a non-rigid connection between each shaft and its respective cylinder, and gear segments carried by each cylinder adapted to mesh during transfer of a sheet to directly connect the cylinders.

10. In sheet transfer mechanism, rotary cylinders each having gripper elements thereon, a driving shaft for each cylinder, a sleeve journaling each cylinder on its driving shaft, a non- 75

rigid connection between each shaft and its respective cylinder, and gear segments carried by each cylinder adapted to mesh during transfer of a sheet to directly connect the cylinders.

5. 11. In sheet transfer mechanism, members having operation to transfer a sheet from one member to the other, non-rigid driving means for at least one of said members, and means on each member having coaction during transfer of the 10 sheet and operative to properly position the members relative to each other, whereby transfer of the sheet will be effected in a manner to maintain accurate register of the sheet, the said proper positioning of the members taking 15 place independently of the driving means for that cylinder having the non-rigid connection therewith.

12. In sheet transfer mechanism, members having operation to transfer a sheet from one 20 member to the other, non-rigid driving means for at least one of said members, gripper elements carried by each member for engaging the leading edge of a sheet, and means on each member associated with the gripper elements thereof, said 25 means having coaction during transfer of the sheet to effect alignment of the gripper elements at the moment of transfer, whereby accurate register of the sheet is maintained, the said aligning of the gripper elements taking place independently of the driving means for that cylinder 30 having the non-rigid connection therewith.

13. In sheet transfer mechanism, rotary members each having gripper elements for engaging the leading edge of a sheet, driving means for 25 rotating said members in unison, at least one member having a floating relation with its driving means permitting a circumferential displace- 30

ment of the gripper elements thereof with respect to its driving means, and gear segments on each member having engagement during transfer of the sheet to directly connect the members to accurately align the gripper elements at the moment of transfer. 5

14. In sheet transfer mechanism, the combination with spaced impression cylinders having gripper elements thereon, of a rotary transfer cylinder also having gripper elements thereon and 10 located between said impression cylinders, shafts journaling said cylinders and having a geared relation to rotate the cylinders synchronously, a non-rigid connection between the transfer cylinder 15 and its shaft, and means carried by each cylinder adapted to coact during transfer of a sheet to directly connect the cylinders, whereby the gripper elements thereof are accurately aligned at the moment of transfer.

15. In sheet transfer mechanism, rotary members 20 each having gripper elements for engaging the leading edge of a sheet, driving means for rotating said members in unison, means interposed between at least one member and its driving means whereby said member has a floating 25 relation with its driving means permitting a circumferential displacement of the gripper elements thereof, gear segments on each member, the segments on adjacent members having meshing 30 engagement during transfer of the sheet from one member to the other to accurately align the gripper elements thereof at the moment of transfer, and resilient means associated with one gear segment for forcing said segment outwardly to assure a pitch line contact when meshing 35 with the segment on an adjacent member.

EDWARD F. DUDLEY.
